HEAT EXCHANGE APPARATUS HAVING
ADDITIONAL CONDUCTING PATHS

Peter A. McCuen, Palo Alto, Calif., assignor to Varian
Associates, Palo Alto, Calif., a corporation of
California

Filed July 3, 1961, Ser. No. 121,724
5 Claims. (Cl. 165—185)

The present invention relates in general to electron devices and more particularly to methods and apparatus for efficiently cooling electrodes thereof.

In electron devices such as, for example, traveling wave tubes, klystron tubes, and magnetrons it becomes necessary to cool certain portions of the tube. Typically, in traveling wave tubes and klystrons, heat is generated in the collector electrode, and in a magnetron heat is generated in an anode structure. It has been customary to cool such devices by providing a plurality of cooling fins extending radially circumferentially or radially axially on the hot electrode and then passing a cooling fluid such as air over these fins.

In order to increase the heat transfer from a hot component to a colder cooling fluid it is helpful to increase the area over which the heat transfer occurs. This has led to the practice of increasing the size and the number of fins.

Since the heat transfer from the fins to the cooling fluid is proportional to the product of the fin area and the fin-fluid temperature differential, by enlarging the fins the increase in heat transfer will not be directly proportional to the increase in heat transfer area because the temperature everywhere along the fins will not be equal to that at the fin root or immediately adjacent the hot electrode. Thus, the increased heat transfer due to increased area is partly offset by the decreased average fin-fluid temperature differential.

According to the present invention a high conductance heat path is provided from the hot electrode to an outer portion of the cooling fins which are secured to the hot electrode. In this manner the temperature of the fins is maintained approximately uniform and approximately the same temperature as the hot electrode for more efficient cooling of the electrode.

The principal object of the present invention is to provide novel method and apparatus for efficiently cooling hot elements of electron devices.

One feature of the present invention is the provision of a novel cooling means for an electron device including a high thermal conductance path from a hot element of the electron device to an outer portion of cooling fins on the element.

Another feature of the present invention is the provision of novel cooling means for an electron device including a high thermal conductance member extending radially outwardly from the hot element and axially extending high thermal conductance means connecting said high conductance member to an outer portion of said fins.

Another feature of the present invention is the provision of a novel cooling apparatus for an electron device including a high thermal conductance member extending radially outwardly between at least two radially extending axially aligned fins and circular high thermal conductance means connecting said high thermal conductance member to an outer portion of said fins.

Other features and advantages of the present invention will become more apparent upon a perusal of the following description taken in conjunction with the accompanying drawing wherein:

FIG. 1 is a sectional view of a traveling wave tube embodying the present invention,

2

FIG. 2 is a cross sectional view of the structure shown in FIG. 1 taken along line 2—2 in the direction of the arrows, and

FIG. 3 is an end view of an alternative embodiment of the present invention.

Whereas the invention will be described as specifically applied to a traveling wave tube type of electron device it is obvious that the invention is equally applicable to any electron device having a metallic member constituting an outside portion of the tube envelope such as, for example, a klystron tube, a magnetron, etc.

Referring to FIGS. 1 and 2 of the drawing, a traveling wave tube amplifier 11 includes an evacuated envelope 12 at one end of which is positioned an electron gun structure 13 including a cathode 14 and associated cylindrical anode 15 adapted for generating a beam of electrons. Positioned at the other end of the evacuated envelope 12 is a collector electrode structure 16 adapted to receive the electron beam generated by the electron gun structure 13.

Between the electron gun structure 13 and the collector electrode structure 16 is a slow wave structure shown, for example, as a helix 17 mounted on a plurality of sapphire support rods 18 which are fitted within the envelope 12.

A radio frequency energy input coupling means 19 is provided at the electron gun end of the envelope 12 for applying a radio frequency wave to the slow wave helix 17, and a radio frequency output coupling means 21 is provided at the collector end of the envelope 12 for extracting an amplified radio frequency wave from the slow wave helix 17.

A beam focusing solenoid 22 is positioned around the evacuated envelope 12.

The collector electrode structure 16 comprises a hollow, high thermal conductance core member 24 of, for example, copper the exterior end of which is terminated by an evacuation pinch-off tube 25 molded into an insulator plug 26. A thermally conductive cylinder 27 surrounds 40 and is fixedly secured to the core member 24 and is provided with a plurality of radially directed annular cooling fins 28 which provide a large area for the transfer of heat to a surrounding cooling fluid such as circulating air.

High thermal conductance members 29 of, for example, copper and in the form of solid rings are each positioned between and fixedly secured to two of the fins 28 and form a low thermal resistance path from the cylinder 27 to an outer region of the cooling fins 28. Connection means 31 of, for example, copper in the form of narrow ring segments with an outside diameter that of members 29 and a slightly smaller inside diameter are positioned between and fixedly secured to adjacent cooling fins 28 thereby forming a low thermal resistance path from the member 29 to an outer portion of all the fins 28. By this construction the entire fin can be maintained at approximately a uniform temperature and at approximately the temperature of the core member 24 for the most efficient heat exchange between the cooling fins 28 and the cooling fluid.

As an example of the advantages of the present invention the amount of heat transferred by one collector structure of the type described above was 40% greater than the heat transferred by a finned collector without the additional high conductance structure.

As an alternative to the structure shown the members 29 can be positioned at the end of the collector structure 16 adjacent the cathode to draw off heat from the hottest portion of the collector. Also the connection means 31 can conveniently take the form of rods axially extend-

ing the length of the collector and extending through and secured to each of the fins.

Referring now to FIG. 3 of the drawing there is shown an alternative embodiment of the present invention. A metallic member 41 which can correspond to the core member 24 in FIGS. 1 and 2 is cooled by means of a plurality of radially extending longitudinally directed fins 42 secured such as by brazing to the metallic member 41 and separated from one another by spacer members 43. High thermal conductance members 44 of, for example, copper are provided between certain of the fins 42 for providing a low thermal resistance path from the metallic member 41 to an outer region of the fins 42. High conductance connection means 45 which take the form of circular rings of, for example, copper are connected to the outer end of the members 44 and to all of the fins 42 for conducting heat from the members 44 to an outer portion of each of the fins 42. In this manner each of the fins 42 is maintained at approximately a uniform temperature and at approximately the temperature of the metallic member 41 for the most efficient heat exchange between fins 42 and the cooling fluid.

The metallic member 41 and the core member 24 could be any hot element of an electron device which must be cooled as, for example, the body portion of the envelope 12.

Under conditions of constant fin cross sectional area and constant convective heat transfer coefficient between the fins and the cooling fluid the position at which the high conductance means 31 and 45 contact the cooling fins 28 and 42, respectively, is approximately two-thirds of the radial fin length in a direction outward from the fin root in order to maintain the temperature of the fin approximately uniform. Since there is a limited heat conductance path through the high conductance members 29 and 44 and the connection means 31 and 45 this distance can be made somewhat greater than two-thirds in order to achieve an even more uniform temperature along the fins. The best outward distance along the fins for the connection means would be different if the fins are not of a constant cross sectional area.

Since many changes can be made in the structure set forth above without departing from the scope of the present invention the description and drawings of the present invention are intended to be taken as purely illustrative and not in a limiting sense.

What is claimed is:

1. Cooling apparatus for an electron device comprising, a metallic member defining a longitudinal axis, a plurality of fins radiating from said metallic member, first means substantially transversely oriented with respect to said longitudinal axis forming a low thermal resistance path from said metallic member to an outer portion of said fins, the thermal resistance of said first means being less than the thermal resistance of any one of said plurality of fins, and second means forming a low thermal resistance path, said second means being spaced from said metallic member and coupled to said first means and to said fins whereby the temperature of each of said fins is maintained approximately uniform over the entire fin.

2. Cooling apparatus for an electron device comprising, a metallic member defining a longitudinal axis, a plurality of fins radiating from said metallic member, first means substantially transversely oriented with respect to said longitudinal axis forming a low thermal resistance path from said electrode to an outer portion of said fins, said first means having a lower thermal resistance than any one

of said fins, and second means forming a low thermal resistance path, said second means being spaced from said metallic electrode and coupled to said first means and to said fins whereby the temperature of each of said fins is maintained approximately uniform over the entire fin, said cooling apparatus being adapted and arranged to permit flow of cooling fluid between said plurality of fins.

3. Cooling apparatus for an electron device comprising, a metallic element, a plurality of annular fins radiating outwardly from said metallic element, a high thermal conductance member positioned between and fixedly secured to at least two of said fins and extending radially outwardly from said metallic element, and axially extending, high conductance connection means connecting said high conductance member to an outer portion of said fins, the thermal conductivity of said high thermal conductance connection means being greater than the thermal conductivity of any one of said fins, said high conductance connection means being spaced from said metallic element whereby the temperature of said fins is maintained approximately uniform over the entire fin.

4. Cooling apparatus for an electron device comprising, in a metallic element, a plurality of fins radiating from said metallic element and extending axially thereof, at least one high thermal conductance member positioned between and fixedly secured to at least two of said fins, and circular, high conductance connection means connecting said high conductance member to an outer portion of said fins, said high conductance connection means being spaced from said metallic element to permit the flow of a cooling fluid between said fins, said metallic element, and said high conductance connection means whereby the temperature of each of said fins is maintained approximately uniform over the entire fin.

5. Cooling means for an electron device comprising, a metallic electrode defining a longitudinal axis, a plurality of fins attached to and radiating from said metallic electrode along the length of said electrode, first means forming a low thermal resistance path connected to said metallic electrode and to at least two of said fins, said first means having a lower thermal resistance than any one of said plurality of fins, second means forming a low thermal resistance path outwardly spaced from said metallic electrode and connected to said first means and to said fins at an outer portion of said fins and extending along the length of said electrode, said first and said second means functioning to maintain the temperature of each of said fins approximately uniform over the entire fin.
